(57) **CLAIM**

I claim the ornamental design for a spark plug wire retainer for distributor cap, as shown and described.

DESCRIPTION

FIG. 1 shows a top front left perspective view of a spark plug wire retainer for distributor cap showing my new design.

FIG. 2 shows a bottom front left perspective view thereof;

FIG. 3 shows a front view thereof;

FIG. 4 shows a back view thereof;

FIG. 5 shows a top view thereof;

FIG. 6 shows a bottom view thereof;

FIG. 7 shows a left side view thereof; and,

FIG. 8 shows a right side view thereof.

The broken line shown in the drawings are for the purpose of illustrating portions of the article and form no part of the claimed design.
